UNITED STATES PATENT OFFICE.

EDWHIN O. BRANINGTON, OF ROCHESTER, NEW YORK, ASSIGNOR TO ANDREW HOCHREITER, OF ROCHESTER, NEW YORK.

SIGNAL.

1,136,402.

Specification of Letters Patent. Patented Apr. 20, 1915.

Application filed July 11, 1913. Serial No. 778,546.

To all whom it may concern:

Be it known that I, EDWHIN O. BRANINGTON, of Rochester, in the county of Monroe and State of New York, have invented a new and useful Improvement in Signals, which improvement is fully set forth in the following specification and shown in the accompanying drawings.

The present invention relates to signals and an object thereof is to provide a construction for notifying traffic officers and occupants of following vehicles as to the direction in which the vehicle carrying the signal is to travel, the signal preferably being so constructed that its indications will be visible at night or during day-light.

To these and other ends the invention consists in certain parts and combinations of parts all of which will be hereinafter described, the novel features being pointed out in the appended claims.

In the drawings: Figure 1 is a view showing the indicating face of the signal in elevation; Fig. 2 is a vertical section through the signal showing the semaphore in neutral position; Fig. 3 is a view similar to Fig. 2 showing the semaphore shifted to one of its indicating positions; Fig. 4 is a vertical section through the casing on the line $a-a$, Fig. 2; Fig. 5 is a detail view of the operating mechanism for shifting the indicator or semaphore, and Fig. 6 is a diagrammatic view showing the circuits for operating the signal.

Referring more particularly to the drawings; 1 indicates a casing which may be of any suitable form and have a light source therein, such, for instance, as an incandescent electric bulb 2 as shown. This casing is preferably also provided with a lens or glass 3 which may be colored to give a red light, thus serving as the tail lamp of the vehicle as required by the laws of many States. The casing may also be provided with a lens or glass 4 in one of its lateral side walls for the purpose of projecting a beam of light on the license number of the vehicle on which the signal is arranged. The casing is also provided with two lenses or glasses 5 and 6 for projecting two beams of rays from the light source within the casing and these lenses are preferably uncolored and are preferably also arranged symmetrically on opposite sides of the col-

ored tail lamp 3, in this instance, in a horizontal plane below the plane of the tail lamp.

Within the casing, a semaphore or indicator 7 is provided. This semaphore may be made of transparent material and is preferably colored, for instance, red, in order that when it is shifted between the light source 2 and either one of the openings 5 or 6 a colored or red light will be given by said opening, the normal position of this indicator being below both of the openings 5 and 6, and said indicator being mounted to turn in either direction about an axis 8 from its central or neutral position in order to cover either one of the openings 5 or 6.

The indicator 7 is designed more especially for giving a signal at night and, if one is close to the signal, the position of the indicator may also be determined during the day-time but to insure a more effective signal during the day-time, there may be provided a supplemental indicator preferably in the form of two opposite extending arms 9 and 10 arranged substantially at right angles to each other, shaped like arrows and supported from an arm 11 which extends from and is rigid with the semaphore 7, the casing being provided with the curved slot 12 through which the arm 11 projects. This supplemental indicator is also useful at night as its position in front of the openings 5 and 6 is readily determined.

Any suitable mechanism may be employed for shifting the movable indicators. In this instance, the semaphore 7 has its arm 13 which is pivoted at 8, provided with an arcuate slot 14 above its pivot 8. In this slot a lateral projection 15 on an arm 16 operates, the arm 16 being pivoted at 17 below the pivot of the semaphore and being notched at 18 so as to pass about the pivot 8 when the parts are in the position shown in Fig. 3. Below the pivot 17, the arm 16 is formed with a slot or way 19 in which works a lateral projection 20 on an arm 21 which is pivoted above the pivot 8 and to one side of the projection 20 and which carries a depending armature 22 on the other side of the projection 20. With this arrangement, a small movement of the lever 21 is multiplied in the lever 16 and is still further multiplied in the semaphore arm 13, thus permitting the semaphore 7 to be shifted to either side

of its neutral position through the medium of electro-magnets. The latter are arranged in two pairs 23 and 24 arranged on opposite sides of the armature 22. These magnets 5 may be connected to a common battery 25 and controlled from a common switch 26 movable to the contacts 27 and 28 to close the circuits to the magnets 23 and 24 respectively, the switch 26 being located in proximity to the steering wheel in order that the operator may control the signal from the seat of the vehicle.

The signal may be mounted on the front or the rear end of the vehicle or signals may 15 be mounted on both ends. When mounted on the front end of a vehicle, it serves to notify traffic officers of the direction in which the vehicle intends to travel and, when mounted on the rear end, it serves to 20 notify following vehicles of the direction of travel of the vehicle. The operator of the vehicle, as he approaches the turning point, shifts a switch 26 to energize the magnets 23 or the magnets 24, depending on whether the 25 vehicle is to be turned to the left or to the right. Assume the magnets 24 are energized, the armature 22 will be drawn toward such magnets, shifting the lever 21 which in turn shifts the lever 16 that shifts the semaphore 30 arm 12 thus causing the semaphore 7 to be interposed between the light source 2 and the opening 6 in the casing, at the same time shifting the arrow 10 over the opening 6, thus giving two indications to the following 35 vehicles of the direction in which the vehicle containing the signal is to turn. The transparent semaphore 7 is especially adapted for night use while the arrow 10 gives a better day signal. After the vehicle has turned a 40 corner, the switch 26 is turned to its neutral position, thereby deenergizing the magnets and permitting the semaphore 7 with the arrows 9 and 10 to drop to neutral positions under their own weights, ready to be shifted 45 again either to the right or to the left. The signal also acts as a tail lamp to the vehicle and serves further to illuminate the license sign.

One of the main features of this invention 50 is the arrangement of the three lamps one between and slightly above the other two so that this lamp is preferably colored combines with either of the other lamps to denote the direction of turning of the vehicle. 55 It is apparent that the two lower lamps may be used alone for giving indications of the directions of travel of the vehicle but the combination of the three is more effective as it produces an immediate impression on 60 the mind as to the direction the vehicle is to travel and this is especially true when both the transparent semaphores and the upper light are colored the same so that two colored lights and one white light are visible as 65 a signal.

What I claim as my invention and desire to secure by Letters Patent is:

1. A signaling device comprising a casing having two openings and also having a third opening situated between the first two openings and having a colored glass therein, a light source within the casing, and transparent means adapted to be interposed between the light source and either one of the first two openings for causing either of the first two openings to project a colored light, said transparent means being normally positioned so that both of the first two openings will simultaneously project an uncolored light. 70

2. A signaling device comprising a casing having two openings, a light source within the casing, and a transparent colored semaphore arranged to be interposed between the light source and either of said openings in 85 order that a colored light may be projected by such opening, said semaphore being in its normal position out of coöperative relation with either of the openings and hidden by the casing so that both openings may simultaneously project an uncolored light. 90

3. A signaling device comprising a casing having two openings, each of which has an uncolored glass therein, said casing also having a third opening situated between the first two openings and having a colored glass therein, a light source in the casing, and means normally out of coöperative relation with both of said openings so that said openings may simultaneously project uncolored 95 light, said means being operable to coöperate with either of the openings to cause such opening to project a colored light. 100

4. A signaling device comprising a casing having two openings, each provided with an uncolored lens, a light source within the casing, and a transparent colored semaphore normally lying hidden by the casing between the two openings so that the latter may project uncolored lights but movable to either 105 side of its normal position to be interposed between the light source and either of the lenses to cause such lens to project a colored light. 110

5. A signaling device comprising a casing 115 having three openings, one arranged between the other two and provided with a colored glass, a light source within the casing, a transparent colored semaphore normally lying at a point between the other two openings, and means for moving said semaphore to either side of its normal position in order to cause the semaphore to coöperate with either of the openings. 120

6. A signaling device comprising a casing 125 having two openings, a light source within the casing, a transparent colored semaphore normally lying out of coöperative relation with both openings and hidden by the casing, and two electromagnetic devices one 130

for moving the semaphore in one direction to coöperate with one of the openings and the other for moving said semaphore in the other direction to coöperate with the other opening.

7. A signaling device comprising a casing having three openings, one arranged between the other two and provided with a colored glass, a transparent semaphore normally lying out of coöperative relation with both of said openings, and two electromagnetic devices, one for moving said semaphore in one direction from its normal position to coöperate with one of said two openings and the other for moving the semaphore in the opposite direction from its normal position for coöoperating with the other of said two openings.

8. A signaling device comprising a casing having three openings, one of which is arranged between the other two, and is provided with a colored lens and the other two openings being provided with uncolored lenses, a light source within the casing, and a transparent semaphore having a color corresponding to the color of the intermediate lens and adapted to coöperate with either of the uncolored lenses to modify the light projected by such lens.

9. The combination with a semaphore movable to either side of a vertical normal position and pivoted near its upper end so as to maintain the vertical normal position by the action of gravity, said semaphore

having a slotted portion, of a lever pivoted 35 between its ends and having the longer arm thereof provided with a projection operating in the slotted portion of the semaphore, a second lever pivoted at its upper end, and having, between its ends, a pin and slot connection with the first mentioned lever, and also having an armature at its lower end, and electromagnets arranged on opposite sides of said armature to shift the latter in opposite directions.

10. The combination with a member pivoted near its upper end and movable in opposite directions from a central normal position, of a lever pivoted below the pivot of said member and having a pin and a slot connection with said member above the pivot of the latter, a second lever pivoted above the said member and having a pin and slot connection with the first named lever below the pivot of said lever, an armature depending from said second lever below the pin and slot connection, and electromagnets arranged on opposite sides of the armature.

11. A signaling device comprising a casing having two openings, a light source within the casing, and two indicators, one within the casing, and one on the exterior of the casing and both being simultaneously movable to coöperate with either of the openings.
